COMBINED PLAYGROUND CLIMBER AND SLIDE

Ronald W. Zick, Jonesville, Mich., assignor to Game
Time, Inc., Litchfield, Mich.

Filed Mar. 19, 1970, Ser. No. 21,984

Term of patent 14 years

Int. Cl. D21—03

U.S. Cl. D34—5

FIG. 1

FIG. 2

FIG. 3

FIG. 4

FIG. 1 is a side elevational view of combined playground climber and slide constructed in accord with my new design,

FIG. 2 is a top plan view of my new design,

FIG. 3 is a front elevational view of the combined playground climber and slide as taken from the right of FIG. 1, and

FIG. 4 is a rear elevational view of the new design as taken from the left of FIG. 1.

I claim:

The ornamental design for combined playground climber and slide, substantially as shown.
